UNITED STATES PATENT OFFICE.

FRANK HUSTON, OF LEWIS, KANSAS.

BOX-LID HOLDER.

1,116,285.

Specification of Letters Patent.

Patented Nov. 3, 1914.

Application filed January 3, 1914. Serial No. 810,223.

To all whom it may concern:

Be it known that I, FRANK HUSTON, a citizen of the United States, residing at Lewis, in the county of Edwards and State 5 of Kansas, have invented new and useful Improvements in Box-Lid Holders, of which the following is a specification.

This invention relates to box lid holders and more particularly to combined lid holders, box openers, seal scrapers and nail extractors.

The object of the invention is to provide a simple and efficient device constructed entirely of one piece of material and arranged 15 so as to provide means for destroying the seal, opening and extracting the nails of cigar boxes and supporting the lids in open position.

Further objects of the invention will appear as the following description is read in 20 connection with the accompanying drawing, which forms a part of this application, and in which:—

Figure 1 is a perspective view showing the 25 device applied to a cigar box as a lid holder. Fig. 2 is a perspective view of the device removed from the box. Fig. 3 is a perspective view of a modified form.

Referring more particularly to the drawing, 1 represents the body of the device which is tapered upon its rear side toward one end, as shown at 2, so as to provide a thin edge which is sharpened, as at 3, whereby the tapered end is readily adapted for 35 destroying the seal on a cigar box and for entering beneath the lid so that it may be prized open. A notch 4 is formed in one side which extends from front to back and is arranged to receive and extract a nail 40 from the lid of the box. The upper end or the end opposite the tapered one has the front enlarged, as shown at 5, and in the bottom portion of the enlargement the re-

cess 6 is formed to receive the side 7 of the cigar box 8.

Formed in one side of the body at right angles to the recess 6 is a longitudinal groove or recess 9 which opens at its lower end onto the front and is arranged to receive the lid 10 of the box, as shown in Fig. 1.

By providing a tool of this character the packed box may have its seal destroyed by the use of the edge 3 and the lid prized open by the tapered end. The nail may then be extracted by engaging the same in the notch 55 and using the chisel end of the device as a fulcrum. After the box has been opened and the lid turned into vertical position the device may be engaged with the lower edge of the lid and with the side, as shown in 60 Fig. 1.

In the modified form shown in Fig. 3 the upper end of the body is tilted at an angle to the lower end so that when the device is applied to a box the lid will be inclined rearwardly, as will be readily understood.

What is claimed is:—

A device of the class described comprising an elongated body tapered at one end from one side only, and an enlargement 70 formed at the other end of the body and at the opposite side from the tapering portion; said enlargement having a notch or recess in the lower end thereof, said body having a longitudinal groove arranged upon the side 75 of the body at right angles to the notch or recess, said groove opening at its bottom immediately below the enlargement and at the side of the device adjacent the recess.

In testimony whereof I affix my signature in presence of two witnesses.

FRANK HUSTON.
